CLAIM

The ornamental design for a bird feeder, as shown and described.

DESCRIPTION

FIG. 1 is a right front perspective view of a bird feeder showing my new design;

FIG. 2 is a top plan view thereof;

FIG. 3 is a bottom plan view thereof;

FIG. 4 is a front elevational view thereof; the rear elevational view being a mirror image of the front view shown; and,

FIG. 5 is a side elevational view thereof; the opposite side being a mirror image of the side shown.

FIG. 1

FIG. 2

FIG. 3

FIG. 4

FIG. 5
